UNITED STATES PATENT OFFICE.

JOHN W. ELLIS, OF PORTLAND, MAINE, ASSIGNOR TO L. H. NELSON COMPANY, A CORPORATION OF MAINE.

COLLAPSIBLE CLOCK-CASE.

984,201.

Specification of Letters Patent. Patented Feb. 14, 1911.

Application filed October 28, 1910. Serial No. 589,593.

To all whom it may concern:

Be it known that I, JOHN W. ELLIS, a citizen of the United States, residing at Portland, county of Cumberland, State of Maine, have invented certain new and useful Improvements in Collapsible Clock-Cases, of which the following is a specification.

This invention relates to clock cases, and particularly to folding clock cases. In the manufacture of articles of this sort it has become desirable in certain instances to supply the cases separate from the works and in such instances it has been desired to produce a case which should be capable of being packed in minimum bulk. In clock case construction, however, it is necessary to have a considerable stability and, where the case is to be offered for sale with a choice of works or with removable works, it is of great advantage to have a case into which the works can be fitted or from which they can be removed with a minimum amount of trouble.

It is the object of my present invention, therefore, to provide a clock case which shall be collapsible into a flat state for shipment or storage and yet which, when set up, will afford all the requisite strength and stability of structure, and to which the works may be applied with the greatest ease, and when so applied will be in sufficiently permanent relation to the case to afford them full protection. This result I accomplish by a construction and arrangement of the parts which will be more fully described in the specification which follows and, for the illustrations of which I have shown in the drawings a form which I find well adapted to practical use.

In these drawings and in the specification like reference numerals are employed to indicate corresponding parts and in the drawings:—Figure 1 is a front elevation of the clock case with works applied, showing in dotted lines some of the interior construction. Fig. 2 is a top view of the case and works as shown in Fig. 1, and Fig. 3 is a top view of the case in a state of partial collapse.

To the front 1 I flexibly unite, as by hinges 2 and 3, a pair of sides 4, 4 and to these I unite a back 5 by hinges 6 and 7. The hinges 3 and 6, which are set diagonally opposite, are formed so as to open and close between the right angle of their normal position when set up and the various obtuse angles to their

open position when their adjacent sides lie flat. The hinges 2 and 7 are constructed to open and close between the right angle position which they occupy when the case is set up through the acute angles until their 60 adjacent sides lie folded together.

The front 1 has an opening 1¹ of substantially the diameter of the clock barrel, which is indicated as 8, while the rear side is provided with an opening 5¹ of slightly smaller 65 diameter adapted to expose the rear side of the clock barrel.

On each of the inner faces of the sides 4, 4 I provided a pair of inwardly disposed spring members 9, 9 having curved inner portions adapted to conform to the cylindric sides of the clock barrel 8. These springs are yieldably lateral so that the clock barrel may be pressed down between them from above until it is supported in registry 70 with the opening 1¹ in the front 1 and in alignment with the opening 5¹ in the back 5. Below these side springs 9 is pivoted a forming piece 10 having the contour desired for the transverse section of the case. The forming 75 piece 10 is hinged at 11 to one of the sides 4 and is notched at its opposite end, as indicated at 10¹, so as to pass the opposite side spring 9. The forming piece 10 is also slotted, as indicated at 13, so that when 80 folded up the spring 9 will be permitted to pass through it. In collapsing, one of the side springs 9 passes through the opening 5¹ at the back 5 while the opposite spring passes 85 through the opening 1¹ of the front 1, thus 90 permitting the structure to lie perfectly flat. The forming piece 10 may be so spaced with regard to the opening 1¹ as to form a support for the works, as well as a contour plug 95 for sustaining the case against collapse.

In assembling the works 8 with the case, after the case has been set up, the barrel is thrust in through the open top, which is of just sufficient width to receive it.

14, 15 and 16 are the usual handles or 100 knobs for winding the main and alarm springs and for setting the hands. In most instances the handles are hinged to fold down flat so that they do not project beyond the rear end of the barrel until they are 105 turned up for use. They are, however, readily accessible through the rear opening 5¹.

Various modifications may be made in the form and finish of the case and in the con- 110

struction and arrangement of the parts, all without departing from the spirit of my invention if within the limits of the appended claims.

5 What I, therefore, claim and desire to secure by Letters Patent is:—

1. A collapsible clock case comprising a front wall having an opening therein substantially the diameter of the clock barrel, 10 a rear wall and a pair of side walls each flexibly hinged to each of said front and rear walls forming a continuous structure vertically rigid but laterally collapsible and means for holding said clock case against collapse and for supporting a clock barrel in registry with said opening.

15

10 a rear wall and a pair of side walls each flexibly hinged both to the front and to the rear walls forming a continuous structure vertically rigid but laterally collapsible, a forming piece movably mounted with reference to said walls and fitting therebetween and adapted when in normal transverse position to hold said case walls against collapse and means above the transverse posi-

tion of said forming piece for holding a clock barrel in registry in said opening.

2. A collapsible clock case comprising a front wall having an opening therein of substantially the diameter of the clock barrel, a rear wall and a pair of side walls each 25 flexibly hinged to each of said front and rear walls forming a continuous structure vertically rigid but laterally collapsible and means for holding said clock case against collapse and for supporting a clock barrel in registry with said opening.

In testimony whereof, I affix my signature in presence of two witnesses.

JOHN W. ELLIS.
